DEVICE FOR DISTRIBUTING SILAGE

Lester B. Murray, Kenosha, Wis.

Application August 25, 1938, Serial No. 226,817

2 Claims. (Cl. 302—60)

This invention relates to an improved device adapted to be disposed beneath the open end of the outlet pipe of a silo filling machine to distribute and spread the ensilage as it is dispensed into the silo.

More particularly, it is an object of this invention to provide an annular diverging member adapted to be positioned beneath an outlet pipe with its converging end uppermost to distribute the material being dispensed from said pipe outwardly in all directions.

Still a further object of this invention, is to provide an annular diverging distributor adapted to be disposed with its converging end adjacent to an outlet pipe and having its diverging end flared outwardly to form an annular baffle for broadcasting the material dispensed from a pipe.

Still a further object of the invention, is to provide means adapted to be connected to an inverted cone shaped distributor for removably positioning said distributor beneath the open end of a pipe.

Other objects and advantages of the invention will hereinafter become more fully apparent from the following description of the drawings, which illustrate a preferred form of the invention, and wherein:

Figure 1 is a side elevational view showing the device disposed beneath an outlet pipe,

Figure 2 is a top plan view of the device as seen in Figure 1,

Figure 3 is a vertical central sectional view taken on the line 3—3 of Figure 2,

Figure 4 is a view similar to Figure 2 showing a modified supporting means for the distributor,

Figure 5 is a vertical central sectional view partly in elevation of the distributor as seen in Figure 4,

Figure 6 is a view similar to Figure 1 of the distributor provided with another modified form of supporting means, and

Figure 7 is a side elevational view, partly in section taken at right angles to Figure 6.

Referring more particularly to the drawings, wherein like reference characters designate like or corresponding parts throughout the different views, 10 designates a portion of a conventional outlet pipe adapted to be connected to a silo filling machine, not shown, as seen in Figure 1, which is shown merely to illustrate the application of the distributor comprising this invention and which will hereinafter be described.

The distributor includes a cone shaped member 11 which is provided with the outwardly flared portion 12 at its enlarged end, and which is

adapted to be positioned beneath the open end of the pipe 10 with its closed restricted end 13 uppermost or adjacent to pipe 10.

The distributor 11 may be removably mounted beneath the pipe 10, as indicated in Figures 1, 2 and 3 by means of the supporting members 14 which have their corresponding ends 15 bent to engage the inner side of the cone 11 and to be secured thereto by the fastenings 16, with the intermediate portion extending outwardly and upwardly from the diverging end thereof and with their opposite ends bent to extend toward each other to connect with the intermediate portion of the arcuately shaped corresponding clamping members 17, which are connected at 15 their opposite ends by means of the nut and bolt fastenings 18. Clamping members 17 are adapted to be removably connected to pipe 10, as seen in Figure 1, by means of their fastenings 18 to position the cone 11 beneath the open end thereof with its closed end 13 uppermost or adjacent to the pipe 10.

As seen in Figures 6 and 7, the supporting members 14' adjacent their upper converging ends are bent as seen at 19 to offset their upper converging ends from their intermediate portions and to offset the cone 11 from the clamping members 17, so that the cone 11 when positioned beneath the pipe 10 will be disposed in offset relationship relatively to the axis of its outlet end. This is important where the material is being dispensed through pipe 10 under pressure so that it will be directed downwardly and outwardly of the pipe 10 rather than directly downwardly, and to insure positioning the distributor 11 in the line of flow of the ensilage it should be offset relatively to the pipe 10 by means of the supports 14'. As best seen in Figure 7, the supporting members 14' are shaped slightly different from the members 14, in that their upper portions 20, in which are provided the portions 19, are offset inwardly relatively to the lower portions 21 by means of the diagonally disposed intermediate portions 22.

In Figures 4 and 5, another form of supporting means for the distributor 11 is shown, comprising a bracket 23, which is adapted to have its opposite corresponding ends secured by means of the fastenings 16 to the inner side of the cone 11, with its intermediate portion 24 disposed transversely of the axis of the cone and provided with an opening to receive one end of a rod 25 which extends through the restricted end 13 and which is adjustably positioned relatively to the cone by means of the fastenings 26 engaging the lower end of the rod 25 above and beneath the portion 55

24. The opposite end of the rod 25, is adjustably positioned and connected to a lug 27, through which it extends, by means of corresponding fastenings 26 which engage the upper end of the rod 5 25 above and beneath the lug 27. Lug 27 is formed integral or secured to one of the clamping members 17 which are adapted to be connected to a pipe 10, as heretofore described. The intermediate portion of the rod 25 is curved, to position the cone 11 beneath the pipe 10, now shown, and may be bent sufficiently to dispose it centrally of the open end of said pipe, as in Figure 1, or offset relatively to the open end as in Figures 6 and 7. Rod 25 is preferably threaded at its opposite ends so that the fastenings 26 in the form of nuts may be employed to adjustably mount it relatively to the clamps 17 or to the cone 11.
- 10 15 20 Various changes may be resorted to provided

they fall within the spirit and scope of the invention.

I claim as my invention:

1. A device of the class described comprising a cone shaped distributor, a pair of arms having inwardly and upwardly extending corresponding ends secured to the inner side of the cone shaped distributor, said arms having diametrically opposed intermediate portions extending upwardly from the enlarged lower end of the distributor, and the opposite ends of said arms being offset inwardly from the intermediate portions for detachably engaging the outlet end of a discharge pipe for supporting the distributor therebeneath. 5 10

2. A device as in claim 1, said last mentioned ends being laterally offset relatively to the first mentioned ends for positioning the distributor in offset relationship relatively to the axis of the outlet end of the discharge pipe. 15
